ABSTRACT: A statistical display apparatus for displaying information about the magnitude of a variable in histogram form comprises a number of capacitors corresponding to the number of classes into which the magnitude of the variable is to be classified. The variable is periodically sampled and, in accordance with the magnitude of the sample, an appropriate capacitor is selected by a stepping-switch unit and a unit charge is fed into the selected capacitor. In this selection, all the capacitors are scanned by the stepping switch and part of the charge is removed from each capacitor. The capacitors are also scanned in sequence and the magnitudes of their charges are displayed on a cathode-ray tube.

STATISTICAL DISPLAY APPARATUS

BACKGROUND OF THE INVENTION

1. Field of the Invention

This invention relates to apparatus for the statistical display of a variable, for example randomly varying analogue quantity, and is directed more particularly to providing a histogram-type display indicating the frequency with which the magnitude of the variable falls within predetermined classes, that is to say between predetermined ranges of values, and in which the display continuously updated.

2. Description of the Prior Art

In a conventional-type of histogram display, a variable is periodically sampled and, over a period of time, a count is made of the number of times in which the sample value falls within the various classes. The various counts can be displayed so as to give a histogram-type display. It is necessary however, at the end of the counting period, to remove the information and restart counting. In this type of system, the display information is only of significance towards the end of a counting period and for many purposes it can be utilized only at the end of the period. The present invention however is directed to a system in which the display is continuously updated by the removal of stale information so that the display is continuously of significance in indicating the required information.

An updated histogram display has been described in U.S. Pat. No. 3,317,132 of R. E. Martin making use of a mechanical system using balls which are fed into tubes to build up a histogram display or of a digital system using digital processing techniques.

SUMMARY OF THE INVENTION

It is an object of the present invention to provide an improved form of statistical display apparatus for giving an updated form of statistical display apparatus for giving an updated histogram display making use of analogue techniques enabling information in histogram form to be available as analogue voltages, suitable for example for displaying directly on a cathode ray tube.

According to this invention, a statistical display apparatus for displaying information about the magnitude of a variable comprises a number of capacitors corresponding to the number of classes into which the magnitude of the variable is to be classified, means for periodically sampling the variable and classifying its magnitude into the appropriate one of the classes and for feeding a charge into the capacitor corresponding to the appropriate class, means for periodically removing part of the charge on each of the capacitors and display means for displaying the magnitude of the charges or mean charges on each of the various capacitors.

A charge may be introduced on to a capacitor either by connecting the capacitor through a resistance to a source of charging potential for a time period short compared with the time constant of the charging circuit or by connecting the capacitor to an auxiliary capacitor which has previously been charged. For convenience in the following description, the various capacitors corresponding to the different classes will be referred to as the storage capacitors as they form the data stores. As will be explained later, under steady state conditions, if all the storage capacitors are of equal magnitude and if all the charging and discharging circuits are the same or similar, the voltage on each of the storage capacitors is directly proportional to the frequency with which the variable is classified into the appropriate class. This form of apparatus however has the particular advantage that under changing conditions, the display is more closely representative of recent sampled information than of stale information. That this is so may readily be seen by considering a storage capacitor into which some charge has been put in the past but where no recent sampled values fall within this class. It will be appreciated then that this capacitor will be discharged exponentially, i.e. the rate of loss of charge is greater initially than it is later. The charge on the capacitor is therefore less than would

be the case if the sampled values in this class had been coming in at a uniform rate corresponding to a true average frequency over a period of time. If on the other hand recent samples are falling frequently in this class the charge will tend to build up exponentially and the charge will be higher than if the sampled values had been received uniformly over a period of time at the actual average rate over that period.

The display means may conveniently be a cathode-ray tube display, the voltages on the various storage capacitors being scanned in sequence and utilized to effect transverse deflection of a line scan trace so thereby simulating a conventional-type of histogram display. It will be appreciated that such a display on a cathode-ray tube can be obtained as frequently as is required; in effect one can obtain a continuous display in histogram form of the classification of the magnitude of the variable quantity. Other types of indicating apparatus however may be employed; for example the voltages on the various storage capacitors may be utilized to control a chart recorder which periodically records these magnitudes or the voltages may be processed electrically, for example they may be utilized in analogue or digital-computing apparatus.

In one simple form of the apparatus the various capacitors corresponding in number to the various classes are made of equal capacity. Each of these capacitors has one of its poles connected to a lead at a common datum potential, for example earth. The other poles of the various capacitors are connected to a common line via separate switches for each of the various capacitors which switches are operated in sequence to complete the circuits for predetermined short durations, the various switches being operated in such a manner that only one capacitor at a time is connected to said common line. For example, this common line is connected to one end of a resistor the other end of which is connected by a further switch enabling that end of the resistor to be connected either to a source of charging potential or left open circuit or connected to a datum potential, conveniently earth. Preferably however a switch unit is employed having separate switch contacts for completing circuits as required through separate resistors to the source of charging potential or a discharge (e.g. zero potential) point. This switch unit is operated in synchronism with the previously mentioned switches but is controlled by the sampling and classifying means so that the charging circuit is completed when the particular switch associated with the particular capacitor corresponding to the class in which the variable is found to fall is closed. The switch unit connects the common line to the datum potential (usually earth) each time the switch associated with a capacitor not corresponding to the appropriate class is closed. It will be seen therefore that when the variable is classified, the appropriate capacitor is connected to be charged through a resistor to receive an additional charge whereas each of the other capacitors will be partially discharged during the switch operation scanning sequence. In this arrangement the output to the display means from the capacitors may conveniently be the voltage on the aforementioned common line. During the switch scanning sequence, this line is connected to the various storage capacitors in succession and hence the switch scanning sequence provides the scanning of the output voltages.

In some cases however it may be preferred to have a separate resistor for each capacitor as this allows the readout circuit to have a different sensitivity for each class. By such an arrangement the histogram scale could be weighted according to the class number.

If the various storage capacitors are to be charged and discharged using an auxiliary capacitor, it is convenient to use a single auxiliary capacitor for both charging and discharging purposes. In such an arrangement, instead of using a resistor between said further switch and said common line, the further switch may be connected directly to said common line and this common line may be connected to one pole of the auxiliary capacitor the other pole of which is connected to a resistor to the source of the datum potential. With this arrangement, whilst the various switches associated with the different

capacitors are open, the further switch has to be closed and opened so as either to put a charge on the auxiliary capacitor or to remove any charge therefrom according as to whether or not the next capacitor to be connected is to be charged or discharged

BRIEF DESCRIPTION OF THE DRAWINGS

The following is a description of a number of embodiments in the invention reference being made to the accompanying drawings, in which:

FIG. 1 is a diagram illustrating a form of statistical display apparatus; and

FIGS. 2, 3 and 4 are diagrams for explaining modifications to the arrangement of FIG. 1. Referring to FIG. 1 there are shown a number of capacitors 10, 11, 12 etc. corresponding to the number of classes into which the variable is to be classified. Typically there are eleven such capacitors. One pole of each of these capacitors is connected to a common line 19 which may conveniently be earthed. The other poles of these capacitors are connected respectively via switches 20, 21, 22 etc. to a second common line 29. These switches 20, 21, 22 may be mechanical switches, e.g. reed switches or they may be electronic switches, e.g. transistors. Mechanical switches are preferred because of a higher insulation when open circuit, preventing loss of charge on the capacitors. These switches are operated in sequence for a period which has to be short compared with the time constant of the charging and discharging circuit for the capacitors to be described subsequently. The various switches are normally open and only one is closed at any one time in a manner to be described later. The common line 29 is connected to a charge/discharge switch unit 30 containing two resistors 31, 32. The resistor 31 is connected between the line 29 and a switch contact 33 leading to a source 34 of direct voltage V whilst the resistor 32 is connected between the line 29 and a switch contact 35 leading to a zero potential source 36.

The switches 20, 21, 22 are controlled to operate in sequence by a switch control unit 40 which gives a switch operating output on a selected one of a set of lines 41 when a signal is received from a timing generator 42, the particular output line 41 being selected by a stepper 43. This stepper is also controlled by timing pulses from the timing generator 42 to step on one step in a cycle sequence for each output signal from the timing generator.

The input information to be displayed may typically be the output signals from a classifier 45 which classifies an analogue input voltage on a line 46 into a number of classes, each corresponding to a selected range of magnitudes of the input voltage and provides an output signals on a selected one of a series of lines 47 corresponding to the appropriate class. One construction of classifier suitable for this purpose is described in the specification of copending U.S. Application No. 743,891 of R. W. Taylor entitled Apparatus for statistically classifying an analogue voltage. The classifier 45 initiates the scanning cycles controlled by the timing generator 42 to effect the cyclic switching of the stepper 43 in synchronism with the sampling, one cycle of the operation of the stepper being effected for each sample. The output from the classifier 45 on the lines 47 is applied to a set of coincidence circuits 48 to which are fed outputs from the stepper 43. The coincidence circuits 48 give output signals on lines 49, 50 when the stepper 43 reaches the step corresponding to the output line 47 selected by the classifier 45. The output on line 49 is applied to the switch unit 30 as a control pulse to effect selection of switch contact 33 in place of switch contact 35. The selected one of the switch contacts 33 or 35 is operated by a timing pulse on a lead 51 from the timing generator 42 in synchronism with the pulses applied to the control unit 40 and the stepper 43.

The switch unit 30 is thus operated synchronously with the switches 20, 21, 22 but is controlled by the classifier 45 so that the line 29 is connected to the voltage source 34 when the par-

ticular one of the switches 20, 21, 22 etc. corresponding to the appropriate class is closed. The line 29 is connected to zero potential source 36 when any of the other switches 20, 21, 22 etc. are closed. A complete scan of all the capacitors 10, 11, 12 is made for each sampling cycle, the switch unit 30 connecting the line 29 to the zero potential source for all the classes except the selected one.

Usually the various capacitors 10, 11, 12 etc. will be made of equal magnitude C. Assuming that the resistors 31, 32 are both of magnitude R, the charging voltage is V, and that the switches 20, 21, 22 etc. are closed for a time, t_s then, if steady state conditions have been reached such that the average rate at which measurements are made in one of the classes C_x is n_x per unit time, the average capacitor voltage V_x will be defined by equating the currents flowing into and out of appropriate capacitors, i.e.

$$n_x \frac{(V - V_x)}{R} t_s = (N - n_x) \frac{V_x}{R} t_s$$

where N is the measurement rate.

$$\text{Hence } V_x = \frac{n_x}{N} V$$

The voltage V_x is thus directly proportional to the frequency at which the sampled values are entering the class C_x .

It will be noted that the capacitor charge in each of the capacitors 10, 11, 12 etc., if no charge is added, is removed exponentially by the repeated connection through the switch contact 35 to the zero potential source in each switch scan. The removal of part of the voltage occurs at the stepwise scanning rate irrespective of the regularity of the scanning or of the measuring rate.

As is indicated diagrammatically in FIG. 1, a cathode-ray tube display 37 is provided with a saw tooth signal applied to the X deflection system from a time base generator 38 to give a scanning trace with is synchronized from the timing generator 42 to start at the start of the cyclic scanning sequence of the switches 20, 21, 22 etc. The voltage at the common line 29 is applied, via a modulator 39, to the Y deflection system so that the display trace is a histogram type display. This modulator consists essentially of a switch controlled by the timing generator 42 which switches either the output line 29 or earth to the Y deflection system of the display 37. This modulator is arranged so that the output line 29 is connected to the display only during periods when one of the switches 20, 21, 22 etc. is closed, the display input being earthed at all other times. The timing generator 42 thus controls the sequence of operations which occurs each time the variable is sampled. The sequence of operations is as follows:

1. Stepper 43 is moved to the next step and, on a pulse signal from the timing generator 42, the switch control unit 40 energizes the selected relay coil, the output to the display being earthed by the modulator 39 during this period.

2. The charge/discharge switch unit 30 is operated, the output line 29 being connected either to the constant voltage source 34 via resistor 31 or to zero potential source 36 via resistor 32 according as to the output giving by the coincidence circuits 48. The modulator 39 connects the output line to the display 37.

3. The coil of the selected switch 20, 21 etc. is deenergized and the output to the display earthed. Typically the time period for the first of these operations to the commencement of the second operation would be about 1 millisecond, for the second operation to the commencement of the third about 8 milliseconds and for the third operation to the start of the next sequence about 1 millisecond giving a total time of about 10 milliseconds for a complete scanning sequence. The display is renewed at each measurement and therefore provides a continuously updated relative frequency histogram having the basic properties of a probability function.

It may be desired to indicate on the display the particular class in which an entry is being made. This is done by providing an output from the coincidence circuits 48 on the line 50 which is applied as a brightening pulse to the display when the stepper is in a position corresponding to the class being entered.

If it is required to have a normal histogram display showing the frequency of entry into the various classes for a predetermined period without any updating, this can be achieved by not discharging the capacitors and by charging the selected one from a constant current source. FIG. 2 illustrates a modified circuit arrangement for the switch unit 30 suitable for this purpose. In FIG. 2, by putting a switch contact 52 in its left-hand position, the circuit arrangement is effectively that of FIG. 1, having resistors 31, 32, switch contacts 33, 35, a constant voltage source 34 and a zero potential source 36. When switch contact 52 is in its right-hand position, the line 29 can be connected by a switch contact 53 to a constant current source 54 or, by a switch contact 55, through a resistance 56 to a zero potential point 57. The switch 52 may be a manual switch set as required. For a normal (i.e. not updated) histogram display giving the frequency of entry into classes within a predetermined period, the switch 52 is put to the right-hand position, switch 55 is left open circuit and switch contact 53 is operated by the coincidence circuits so as to be closed once in each scanning cycle when the stepper 43 is at the position corresponding to the class to be entered. With a constant current source, the capacitors 10, 11, 12 etc. are charged linearly proportional to the number of entries. The accuracy in relation to the period over which measurements are made will depend on the quality of the storage capacitors 10, 11, 12 etc. and on the impedance of the readout circuit. It would be possible to use the switch contact 52 in the right-hand position for an updated display by operating the switch contact 55 for each step of the scanning to remove part of the charge on the capacitors 10, 11, 12 in a manner similar to the operation of switch contact 35 of FIG. 1. In this case, however, since the capacitors are linearly charged, it is desirable to remove part of the charge from every capacitor during the cycle not merely those to which an entry is not to be made. For this reason, in this case operation 2 as set out above would be divided into two equal intervals. In the first of these intervals, if the stepper is in a position corresponding to the entered class, switch 53 would be closed to increase the charge in the capacitor. In the second interval, whatever the position of the stepper 43, the discharge resistor 56 would be connected in circuit by switch contact 55. Other forms of display are possible; for example in FIG. 1, by leaving switch contact 35 open, a histogram display is produced representing all entries into the various classes for a predetermined period but in which the vertical deflection scale is exponential.

If it is required to provide a permanent record, a chart recorder may be connected to the common line 29 instead of or in addition to the cathode ray tube display 37. A sequential operation of the switches 20, 21, 22 would then have to be carried out at a rate appropriate to the recorder performance. This would be normally much slower than the sampling rate and it would be convenient therefore to interrupt the sampling leaving the switch unit 30 inoperative whilst a record is made on the chart recorder. This histogram would thus be plotted on the chart, the class width axis being provided by the chart traverse. It will be noted that all the capacitors 10, 11, 12 etc. are isolated when they are not being charged or discharged. The time for which a given voltage distribution on the capacitors can be stored is therefore determined primarily by the quality of the capacitors.

FIG. 3 illustrates a modification of part of the system of FIG. 1 and mention will only be made of the distinctive features of FIG. 3. It will be noted that the switch unit 30 of FIG. 1 functions essentially as if it were a switch having a normal position in which there is an open circuit but which serves to connect the line 29 either to the constant voltage source or to the zero potential point. Considering such a switch it will be

seen that, instead of using two resistances 31, 32 in the two alternative circuits, a single resistor might be provided between the switch contact and the line 29. In FIG. 3 such a switch arrangement is shown but, instead of a single resistor between the switch and the line 29, there are shown separate resistors 70, 71, 72 provided for each of the capacitors 10, 11, 12 etc. The switch now is a contact arm 74 which is normally in an open circuit position but can move either to a charging circuit from a charging potential source 75 or to a zero potential point 76. The use of separate resistors 70, 71, 72 allows the readout circuit to have a different sensitivity for each class into which the magnitudes of the variable are classified. In FIG. 3, to effect this readout, separate transistors 80, 81, 82 are provided for each class. The collector of each transistor is connected to a suitable source of supply potential. The bases of the various transistors are connected to the respective junctions between the resistors 70, 71, 72 etc. and the switches 20, 21, 22 etc. The emitters of the various transistors are connected through resistors 85 to the modulator 39 and thus to the display 37 and also via common load resistor 57 to the line 19. It will be seen that, when the various switches 20, 21, 22 are closed, the outputs remaining in the respective transistors are applied to the display. The arrangement of FIG. 3 might be used for example if the histogram scale is to be weighed according to the class number so as to give a display in which vertical deflections are proportional to $(n/N) d$ where d is the deviation.

FIG. 4 illustrates another modification of the arrangement of FIG. 1 in which an auxiliary capacitor 90 is used to transfer charges to and from the storage capacitors 10, 11, 12 etc. instead of using the resistive charging and discharging switch unit 30. As shown in FIG. 4 the arm of a switch 91 is connected directly to the common line 29 and this line is connected to one pole of the capacitor 90 the other pole of which is connected through a resistor 92 to ground. The switch 91 is normally open circuit but can connect the line 29 either to a charging potential source 93 or zero potential point 94. With the arrangement of FIG. 4 the switching sequence has to be slightly different from that of FIG. 1 in that the switch 91 has to be closed and opened so as to put the appropriate charge on the auxiliary capacitor 90 before each operation of each one of the switches 20, 21, 22 etc. Thus the cycle of operation is first the closing of one of the contacts of the switch 91 by moving the arm of the switch either to the lead to the source 93 or the lead to the zero potential point 94 according to whether or not a charge is to be added to a storage capacitor 10, 11, 12 etc. The switch arm 91 is then put in the open circuit position and the appropriate one of the switches 10, 11, 12 is closed and subsequently reopened. This transfers charge from the capacitor 90 to one of the storage capacitors 10, 11, 12 or removes part of the charge from one of these storage capacitors by sharing it with auxiliary capacitor. Subsequently the switch arm 91 is moved to make contact with the lead to the zero potential point 94 so as to discharge the auxiliary capacitor 90 before starting the operation again for the next one of the storage capacitors. Each time the capacitor 90 is finally discharged, a pulse is generated across the resistor 92 and this voltage is applied to a line 96 leading to the modulator 39 to feed the display. In this arrangement the display will have to be gated so that only the voltage pulse is utilized. The time constant of the circuit constituted by the auxiliary capacitor 90 and the resistor 92 has to be made short compared with the duration of operation of the switches 20, 21, 22 etc. to ensure complete charging and discharging of the auxiliary capacitor 90.

I claim:

1. A statistical display apparatus for displaying updated histogram information about the magnitude of a variable comprising:
a number of storage capacitors corresponding to the number of classes into which the magnitude of the variable is to be classified,

signal amplitude sampling and classifying means for periodically sampling the variable to determine the instantaneous magnitude of the variable and for classifying its magnitude into the appropriate one of the classes in accordance with the determined magnitude, circuit means controlled by said signal amplitude sampling and classifying means for feeding a predetermined unit of charge into the capacitor corresponding to the appropriate class each time the sample falls within the class, means for periodically removing part of the charge on each of the capacitors and display means for displaying the magnitude of the resultant charges on each of the various capacitors.

2. A statistical display apparatus as claimed in claim 1 wherein said storage capacitors are all of equal capacitance and wherein all the charging and discharging circuits are similar.

3. A statistical display apparatus as claimed in claim 1 wherein said display means comprises a cathode-ray tube display.

4. A statistical display apparatus as claimed in claim 3 wherein said display means includes means for scanning the voltages on the various storage capacitors in sequence and means for applying the successively scanned voltages to effect transverse deflection of a line scan trace to simulate a histogram display.

5. A statistical display apparatus as claimed in claim 1 wherein charging of the selected capacitor is effected by connecting the capacitor through a resistance to a constant voltage source for a time period short compared with the time constant of the charging circuit.

6. A statistical display apparatus as claimed in claim 1 wherein charging of the selected capacitor is effected by connecting the capacitor to a constant current source.

7. A statistical display apparatus as claimed in claim 1 wherein charging of the selected capacitor is effected by connecting it to an auxiliary capacitor which has previously been

charged.

8. A statistical display apparatus as claimed in claim wherein the circuit means controlled by the classifying means for feeding a charge into the appropriate capacitor comprises:

5 a common input/output line, a series of switches, one for each capacitor, which switches connect the capacitors to said common input/output line, a stepper for closing and reopening the switches one at a time in sequence, and

10 means for feeding a charging current to said input/output line when the switch corresponding to a capacitor on which the charge is to be increased is closed.

9. A statistical display apparatus as claimed in claim 8 wherein means are provided for connecting said input/output line to a discharge point each time a switch is closed not corresponding to a capacitor on which a charge is to be increased.

15 10. A statistical display apparatus as claimed in claim 8 wherein said means for feeding a charging current to said input/output line comprises a capacitor charge source, a capacitor discharge point, switch means for connecting said input/output line to said charge source on said discharge point, and coincidence circuits for comparing the stepper position with the classified magnitude of the variable from said means for periodically sampling the variable, said coincidence circuit

20 being arranged, on coincidence of the stepper position with the classified magnitude, to operate said switch means to connect said input/output line to said charge source but, on non-coincidence, to connect the input/output line to said discharge point.

30 11. A statistical display apparatus as claimed in claim 8 wherein said input/output line is connected to said display means by a switch operated to effect the connection only when one of the storage capacitor switches is closed.

35 12. A statistical display apparatus as claimed in claim 8 wherein means are provided for initiating a cycle of operation of the stepper each time the variable is sampled.
